COUPLER OPERATING MECHANISM

Donald Willison, Maple Heights, Ohio, assignor to National Malleable and Steel Castings Company, Cleveland, Ohio, a corporation of Ohio

Application December 31, 1956, Serial No. 631,556

10 Claims. (Cl. 213—171)

This invention relates to railway car coupler operating mechanism and more particularly to the bracket structure which supports the coupler operating rod on the end of the railway vehicle.

As is well known to those skilled in the art, the conventional operating rod of coupler operating mechanism is usually attached at its inner or hooked end to a rotor shaft member which actuates the unlocking mechanism of the coupler, and at its outer end is supported on a bracket attached to the end of the car.

In the copending application of Edward Kozak, Serial No. 588,552, filed May 31, 1956, there is disclosed an arrangement of operating mechanism for an interlocking type coupler wherein the rotor shaft member embodies means for preventing operation of the unlocking mechanism of the coupler in the event the coupler is accidentally pulled out of the end of its associated car. More particularly, the Kozak application discloses a rotor shaft member having a slotted section therein through which the hook-end of the operating rod is adapted to pass in the event of an accidental pull-out of the coupler from its associated vehicle, to thereby cause facile separation of the rod and rotor shaft and preclude actuation as well as distortion of the operating mechanism of the coupler. As is well understood by those skilled in the art, unless a coupler, which is coupled to an opposing coupler but which has been pulled out from its associated vehicle, remains in locked condition, it will invariably disengage from its mating coupler and drop to the track bed, where it might cause a train derailment.

When the operating rod of a pulled-out coupler separates from the rotor shaft in accordance with the above identified Kozak invention, the rod is then supported only at its outer end by the bracket on the end of the car. With prior art constructions of brackets, the inner end of the rod drops down toward the track bed, wherein it is in a position to engage one of the wheels of the car, or portions of the track bed. If the rod engages a wheel of the car it may possibly cause a derailment or might interfere with the rotation of the wheel and damage the tread thereof. If the rod catches on a portion of the track bed, it might distort the bracket and rod structure or rip it entirely from the car.

The present invention provides a novel construction of operating rod support bracket that precludes an operating rod that has separated from its associated car coupler from dropping down into a position where it might engage with the wheels of the car or the track bed. More particularly, the present invention provides an operating rod bracket comprising a support shelf extending generally laterally from the inner end of the bracket for supporting the rod and maintaining it elevated above the track bed.

The primary object of the invention is to provide a novel operating rod bracket for supporting the operating rod of a car coupler above the track bed in the event of a separation of the inner end of the rod from the associated car coupler.

Another object of the invention is to provide an operating rod bracket of the latter mentioned type that is simple in design, effective in operation, and economical to produce.

5 A further object of the invention is to provide an operating rod bracket having support means thereon for preventing the operating rod of a car coupler from dropping down into engaged relationship with the track bed or with one of the wheels of the associated railway vehicle, in the event the inner end of the rod is detached from the associated car coupler.

A more specific object of the invention is to provide a novel support bracket for the operating rod of an automatic car coupler, comprising a bearing portion 15 which permits transverse movement of the rod with respect to the car and a shelf extending laterally from the bearing portion toward the car coupler, for supporting the rod above the track bed in the event that the inner end of the rod becomes detached from the coupler.

20 Other features and advantages of the invention will be apparent from the following description taken in conjunction with the drawings, wherein—

Fig. 1 is a front elevational view of the operating mechanism of the coupler in reposed position and showing 25 the novel bracket for supporting the outer end of the operating rod, the coupler being shown in phantom lines.

Fig. 2 is a top plan view of the Fig. 1 arrangement.

Fig. 3 is an enlarged, fragmentary top plan view showing 30 the position that the outer end of the operating rod assumes upon separation of the inner end of the rod from the associated car coupler, and illustrating the function of the shelf portion of the bracket in supporting the rod.

35 Fig. 4 is an enlarged, fragmentary front elevational view of the Fig. 3 arrangement.

Fig. 5 is an enlarged end elevational view taken generally along line 5—5 of Fig. 3, looking in the direction of the arrows.

40 Fig. 6 is an enlarged fragmentary end elevational view, similar to Fig. 5 but showing a modification of the invention.

Referring to the drawings, the coupler operating mechanism is shown applied to a coupler 2 (indicated by dot-dash lines) and the end of a car body 4. The coupler 45 is mounted on the car by means of the usual support structure 6 (also shown in dot-dash lines) and in the embodiment shown is an A.A.R. Alternate Standard Type F Interlocking Coupler. It will be understood, of course, that while the invention has been shown associated with a particular type of coupler, it may be used with any coupler that utilizes an operating or uncoupling rod which at one end is connected to the unlocking mechanism of the coupler, and on the other end is supported on the car structure by means of a bracket.

55 In the embodiment shown, the operating rod 5 is a conventional A.A.R. Standard Operating Rod for the aforementioned type F coupler, and comprises on its inner end a J-shaped hook portion 12 for connection to a rotor shaft member 16 which is mounted on the underside of a coupler head for rotation about a generally horizontal axis. As can be best seen in Fig. 2, the rear side of shaft member 16 is slotted as at 17, to permit facile separation of the rod and shaft member in the event of 60 an inadvertent pull-out of the coupler 2 from car structure 4.

Rotor shaft 16 is connected to the usual unlocking mechanism (not shown) which lifts the lock of the coupler out of locking position and swings open the knuckle 70 upon rotation of rod 5. The outer end of the rod terminates in depending handle portion 18 for actuation

thereof. Adjacent handle portion 18, rod 5 comprises a substantially horizontal portion 20 which is received in the usual U-shaped bearing portion 22 formed by upwardly projecting legs 22a and 22b of bracket structure 24. Bridging means, such as cotter pin 23 and associated roller member 25, are attached to the upper end portion of both legs and thus close the upper end of bearing section 22, in the usual manner, to form a closed bearing portion and thus positively maintain rod 5 in assembled condition on the bracket. The inner periphery of bearing portion 22 fits loosely (as shown) around the rod 5 at normal operating positions and permits transverse movement of the rod with respect to the car in response to horizontal angling movement of the coupler 2, as is well understood by those skilled in the art. Bracket 24 also comprises bottom flange portion 26 and upstanding wall portion 28. Wall portion 28 has openings therein for receiving rivets 30 which attach bracket 24 to the end of the car structure 4, for supporting the outer end of the operating rod 5 thereon. As can be best seen in Fig. 3 of the drawings, the inner end of wall portion 28 curves diagonally forwardly as at 32 and merges with the aforementioned bearing portion 22.

In accordance with the invention, a support shelf portion 34 extends laterally inwardly from wall portion 32 and bearing portion 22 of bracket 24, and is adapted to engage portion 20 of the operating rod to support the rod above the track bed in the event that the inner hook-end 12 of the rod becomes detached from rotor shaft member 16 on the coupler. Shelf 34 comprises a generally flat, substantially horizontal bottom wall 36 which is reinforced with upstanding front and rear web portions 36a and 36b extending generally upwardly therefrom and merging with bearing portion 22 and rear wall 28, respectively, of the bracket. As the drawing discloses, the width of the bottom wall 36, as measured between the web portions 36a and 36b is substantially greater than the leg-to-leg width of the opening provided for the rod by the bearing portion 22. It will be seen that shelf portion 34 is disposed at a lower elevation with respect to bearing portion 22 in subjacent relation with the operative position of an operating rod (see rod 5) resting in the U-shaped bearing portion 22. The shelf 34 is disposed at a higher elevation with respect to bottom flange 26 of the bracket. When the operating rod is attached at its inner end to rotor shaft 16 and at its outer end is in normal supported position in bearing portion 22, substantial clearance exists between shelf 34 and the rod so that no interference occurs between the rod and the shelf during rotational or transverse movement of the rod on the car structure.

However, in the event that the inner end of the rod becomes detached from the rotor shaft 16 of the coupler, as for instance would occur if coupler 2 accidentally pulls out from the end of its car, support shelf 34 engages portion 20 of the rod and in conjunction with roller 25 supports the latter above the track bed. In this connection, as coupler 2 is pulled away from the car end, the rod 5 is pulled by the coupler through bearing portion 22 of bracket 24 until handle portion 18 of the rod engages the outer side of portion 22, as is generally shown in Figs. 3 and 4. In the latter position, it will be apparent that no further transverse sliding movement of the rod, with respect to the bracket, can occur as the coupler continues to be pulled outwardly of the car. With a rotor shaft embodying the slotted construction, as disclosed in the aforementioned Kozak application, the inner end 12 of the rod will pass through slot 17 in the rotor shaft head and is no longer supported on the shaft, but drops downwardly toward the track bed, while the outer end of the rod angles vertically about bearing portion 22 until portion 20 of the rod engages wall 36 of the shelf. Thereafter, the

rod bears with its top surface against roller member 25 and with its under surface against wall 36 of the shelf, as shown, to maintain the rod elevated above the track bed and prevent it from becoming entangled with the car or the track bed. It will be noted that wall 36 and front web 36a of the shelf are flared forwardly as at 39 (Fig. 3) to provide sufficient bearing area for all possible angling movements of the rod during separation from the rotor shaft. In this connection, it will be noted from Fig. 5 of the drawings that front web 36a of the shelf is inclined rearwardly to merge with bearing portion 22 of the bracket.

Fig. 6 shows a modification of the invention wherein the support shelf 40 is of generally conically curved section rather than being flat, as in the first described embodiment. The supporting surface 42 of the shelf in this embodiment converges toward and merges with the U-shaped bearing surface 44 of the bracket in a generally symmetrical relationship, as shown. This construction serves to maintain the operating rod in a generally stable, centralized position on shelf 40. In all other operating respects, shelf 40 is similar to the first described embodiment of the invention.

The novel bracket is readily interchangeable with existing types of brackets and does not require any structural changes to be made in the coupler or coupler operating rod. Moreover, it will be apparent that the support shelf portion could be made as a separate part and attached, as by means of welding, to existing constructions of brackets.

From the foregoing description and the accompanying drawings, it will be readily understood that the invention provides a novel operating rod bracket embodying support means for maintaining the rod above the track bed in the event the inner end of the rod is detached from the associated car coupler, and will prevent the rod from becoming entangled with the track bed or associated railway vehicle.

The terms and expressions which have been employed are used as terms of description and not of limitation and there is no intention of excluding such equivalents of the invention described or of the portions thereof as fall within the purview of the claims.

What is claimed is:

1. In combination, a car coupler for a railway vehicle having an operating rod for actuating the unlocking mechanism of said coupler and an operating rod bracket secured to said vehicle, said rod being connected at one end to said coupler and at its other end being supported in relationship to said vehicle on said bracket only, said bracket including a bearing portion for rotatively mounting said rod thereon and integral support means spaced downwardly from said bearing portion to underlie said rod, said support means extending laterally from and diagonally forwardly of said bearing portion, said means being engageable in supporting relationship with said rod in the event the rod becomes detached from said coupler to prevent said rod from dropping to the associated railway track bed.

2. In an arrangement of the type described, a car coupler having a rotor shaft operatively connected to the unlocking mechanism of the coupler, a coupler operating rod connected at one end to said shaft, and a bracket member attached to the associated railway vehicle and forming the sole support for the other end of said rod, said bracket member comprising bearing means, said means permitting both rotational and transverse sliding movement of said rod with respect to said means, and support means integral with and extending laterally and diagonally forwardly from said bearing means in underlying spaced relationship with said rod, said support means being disposed at a lower elevation than said bearing means and being engageable with said rod in the event that the latter becomes detached from said

shaft to prevent said rod from becoming entangled with the associated track bed and railway vehicle.

3. In combination, a car coupler operating rod and a bracket secured to an associated railway vehicle and forming the sole support for one end of said rod, said bracket comprising a raised bearing portion for rotatively mounting said rod thereon and a shelf portion integral with and disposed at a generally lower elevation than said bearing portion, said shelf portion underlying said rod and being engageable therewith in supporting relationship in the event the other end of said rod becomes disassociated from the coupler, said shelf portion comprising a generally horizontal support wall extending laterally and diagonally forwardly with respect to said bearing portion.

4. The combination in accordance with claim 3, wherein said shelf portion comprises generally upstanding front and rear webs disposed respectively adjacent the corresponding extremities of said wall.

5. The combination in accordance with claim 3, wherein in said shelf portion comprises a bottom wall of generally conical section configuration extending laterally from said bearing portion.

6. A bracket for mounting one end of an operating rod of a car coupler on a railway vehicle, said bracket comprising a generally horizontal flange portion and an upstanding rear wall portion for attaching said bracket to the railway vehicle, a shelf portion projecting laterally from one end of said bracket, and a bearing disposed generally intermediate said flange and shelf portions for rotatively supporting the rod thereon, said shelf portion being integral with and disposed at a generally lower elevation than said bearing portion in underlying spaced relationship with respect to the rod, said shelf portion being engageable in supporting relationship with said rod upon predetermined downward angling movement of the latter about said bearing portion, and said shelf portion comprising a generally horizontal wall having generally upstanding webs disposed adjacent the front and rear extremities of said wall.

7. A bracket for mounting an operating rod adapted to operate a car coupler upon manual rotation of the rod, said bracket comprising an upstanding wall having means connected thereto for attaching the bracket to an associated railway vehicle, a bearing portion extending forwardly from said wall for rotatively supporting said rod thereon, and a shelf extending laterally of said bearing portion in underlying spaced relationship with respect to said rod, said shelf being of generally conical section configuration with the top surface thereof con-

verging toward and merging with said bearing portion.

8. A bracket in accordance with claim 7, wherein said bearing portion comprises a transversely extending generally U-shaped bearing surface, said top surface of said shelf merging with said bearing surface in a generally symmetrical relationship in a transverse direction.

9. A bracket for supporting a coupler-operating rod of a railway vehicle comprising, in a normal operating position, a vertical wall, a U-shaped bearing portion supported by the wall entirely to one side of the plane of the wall with one leg of said portion further away from said plane than the other and with its legs joining at the lower closed end of the bearing portion, detachable bridging means extending between and secured to said legs, the bridging means being spaced from said closed end and the legs being spaced to provide the bearing portion with an opening for loosely encircling an operating rod, and a shelf portion having an upwardly-facing potentially rod-supporting surface extending in a direction outwardly from said plane past and beyond said opening along one side of the bearing portion, said surface being of substantially greater width in said direction than the leg-to-leg width of the opening and disposed relatively to the level of the opening in spaced subjacent relation with the normal operative position occupied by an operating rod connected with a coupler and extending through said opening.

10. In combination with a bracket having a U-shaped bearing portion of which the legs are spaced to receive and loosely support the coupler-operating rod of a railway car, a support shelf having potentially rod-supporting surface of substantially greater width than the leg-to-leg width of the bearing portion; and means connecting the shelf with the bracket to position said surface adjacent said bearing portion with said width of the surface aligned in generally parallel opposite but projecting relation with said leg-to-leg width, said shelf being disposed by the connecting means to position said surface in spaced subjacent facing relation with the normal operative position of an operating rod resting in said bearing portion for receiving and supporting said rod in the event of coupler pull-out.
